UNITED STATES PATENT OFFICE

96,038

DESIGN FOR DECORATED WRAPPING PAPER

August Hegmann, Newark, N. J.

Application February 26, 1935, Serial No. 55,620

Term of patent 7 years

To all whom it may concern:

Be it known that I, August Hegmann, a citizen of the United States, residing at Newark, county of Essex, State of New Jersey, have invented a new, original, and ornamental Design for Decorated Wrapping Paper, of which the following is a specification, reference being had to the accompanying drawing, forming part thereof.

The figure of the drawing is a plan view of a portion of a sheet of paper showing my design, the dot and dash lines surrounding the detailed illustration being continued throughout the extent of the paper.

I claim:

The ornamental design for decorated wrapping paper, as shown and described.

AUGUST HEGMANN.
